UNITED STATES PATENT OFFICE.

DONALD G. ROGERS, OF HAMBURG, NEW YORK, ASSIGNOR TO NATIONAL ANILINE & CHEMICAL CO., INC., OF NEW YORK, N. Y., A CORPORATION OF NEW YORK.

PRODUCTION OF ANTHRAQUINONE DYESTUFFS.

No Drawing.

Application filed May 5, 1924. Serial No. 711,047.

This invention relates to improvements in the manufacture and production of diamino-dihydroxyanthraquinone monosulfonic acids from diaminodihydroxyanthraquinone disulfonic acids, particularly diaminoanthrarufine monosulfonic acid from diaminoanthrarufine disulfonic acid and diamino-chrysazine monosulfonic acid from diamino-chrysazine disulfonic acid.

10 It is well known that by reducing diaminoanthrarufine disulfonic acid, or diamino-chrysazine disulfonic acid, with suitable reducing agents under proper conditions, a sulfo-group can be eliminated and leuco-compounds formed which upon subsequent oxidation produce the corresponding diaminodihydroxyanthraquinone monosulfonic acids.

The present invention relates to an improved process for producing such monosulfonic acids from the disulfonic acids.

According to the present invention, diaminoanthrarufine disulfonic acid or diamino-chrysazine disulfonic acid, or a mixture of these acids, is subjected to reduction by the action of zinc dust in the presence of sodium bisulfite and the leuco-compounds of the monosulfonic acids thus produced are subsequently subjected to the action of suitable oxidizing agents in order to obtain the monosulfonic acid of diaminoanthrarufine or of diaminochrysazine, or a mixture of the same. The invention readily effects the production of a leuco-compound of the monosulfonic acid from the disulfonic acid with minimum formation of undesirable by-products, the operating conditions are readily controlled, and the yield and purity of the final product is excellent.

In carrying out the present invention, it is not necessary to start from the diamino disulfonic acids themselves but the corresponding dinitro disulfonic acids of anthrarufine or chrysazine may be used as the initial material, and the production of the leuco-compounds of the corresponding diamino monosulfonic acids can be effected in one operation.

Mixtures of the diamino disulfonic acids of anthrarufine and chrysazine, or mixtures of their corresponding dinitro compounds, can be employed without altering thereby the process of the present invention.

The invention will be further illustrated by the following specific example, but it is un-

derstood that it is not limited thereto. The parts are by weight.

Example: 1280 parts of a 50 percent paste composed of a mixture of the sodium salts of diaminoanthrarufine disulfonic acid and diaminochrysazine disulfonic acid are suspended in 12,800 parts of water at about 30° C. and the mixture neutralized by the addition of sulfuric acid of about 30-35 percent strength. 265 parts of powdered sodium bisulfite (100% purity or its equivalent) are added, and to the well-stirred mixture about 125 parts of zinc dust (100% purity or its equivalent) in the form of a thin aqueous paste or slurry are then added over a period of about 10 to 20 minutes. The mixture is vigorously agitated at about 30°-35° C. for about 20 to 35 minutes, or until a test sample which has been reoxidized with air in the presence of caustic soda is completely insoluble, or nearly so, in dilute sulfuric or hydrochloric acid. If necessary, more sodium bisulfite and zinc dust may be added to complete the reduction. When the reduction is complete, the solution containing the leuco-dye in suspension is separated from excess zinc, if any is present, by centrifuging, decantation, or other suitable method. Common salt is then added to the solution and the precipitated leuco-dye isolated by filtration, or the solution is made alkaline by the addition of caustic soda, and air blown through it for six or eight hours at about 50° C., or until the oxidation is complete. During the oxidation, a major part of the monosulfonic acid will be separated in the shape of their sodium salts which may contain small amounts of zinc compounds or salts. When the oxidation is complete, the sodium salts are either isolated by filtration or the mixture is acidified by the addition of sulfuric or hydrochloric acid and subsequently filtered. The latter procedure gives a product of higher purity, particularly when the diaminodihydroxyanthraquinone disulfonic acid contains impurities. The precipitate is washed with a three to five percent salt solution until free from acid or alkali, as the case may be, and then dried. The precipitate obtained from acid media may be converted into the sodium salt in any suitable manner.

Instead of the oxygen contained in the air, other oxidizing agents such as potassium dichromate, ferric chloride, etc., can be em-

ployed in a suitable manner, as is well known, to oxidize and transform the leuco-compounds into the corresponding monosulfonic acids.

5 In the above example, the procedure may be modified as follows: To 1280 parts of 50 percent paste comprising a mixture of the diamino disulfonic acids of anthrarufine and chrysazine suspended in 12,800 parts water at 10 about 30° C. and neutralized with sulfuric acid, there is added, with good stirring, 53 to 55 parts of sodium bisulfite and 125 parts zinc dust. After a period of 10 to 15 minutes, sulfuric acid of about 30 percent strength is 15 slowly added to the well stirred mixture until the odor of sulfur dioxide can be just detected. Excess of sulfuric acid over that just required to convert the neutral sulfites into acid sulfites, that is, into bisulfites, must 20 be avoided since the presence of free or uncombined sulfuric acid gives rise to low yields and a poor quality of product. After a short time the odor of sulfur dioxide disappears and then a further amount of sulfuric acid is 25 slowly added until sulfur dioxide can be again just detected. This operation is repeated until a test shows that the reduction of the diamino disulfonic acid to a leuco-compound of the monosulfonic acids is complete. 30 From this point, the process is completed as described in the first example.

Instead of adding the sulfuric acid in steps, it may be added more or less continuously at such a rate as to maintain the presence of 35 bisulfites throughout the reduction, care being taken to avoid the presence of free or uncombined sulfuric acid. Additional amounts of zinc dust may be added during the process if found necessary for the completion of the 40 reduction. By this procedure, the neutral or normal sodium sulfite and zinc sulfite formed during the reduction by the action of zinc and sodium bisulfite are converted by the sulfuric acid into their acid sulfites, that is, bisulfites, which in turn react with further 45 quantities of zinc. In this way, the amount of sodium bisulfite initially employed in the reaction need be only about one-fifth, or even less, as much as that required when no sulfuric acid is used. At the completion of the 50 reduction, nearly all of the zinc and zinc compounds are in solution.

In an analogous manner, diaminoanthrarufine disulfonic acid and diaminochrysazine disulfonic acid may be each separately reduced to the leuco-compounds of the corresponding monosulfonic acids which can be subsequently oxidized to the monosulfonic acids.

50 In the specification and claims, it will be understood that the terms "diaminodihydroxyanthraquinone disulfonic acids" and "diaminodihydroxyanthraquinone monosulfonic acids" refer to and include the disulfonic acids and their salts and the monosul-

fonic acids and their salts, respectively, of paradiaminoanthrarufine and paradiamino-chrysazine.

In the process above described in which sulfuric acid is employed, it will be noted that 70 the amount of sodium bisulfite employed is only a small fraction of the amount used when no sulfuric acid is employed. In the absence of sulfuric acid, the reduction may be regarded as based on the following equation:

Upon the addition of sulfuric acid, the zinc sulfite and sodium sulfite produced according to the above equation are regarded as being converted into zinc sulfate and sodium bisulfite as represented by the equation:

As a result of adding an acid during the process, the amount of sodium bisulfite during the reduction remains substantially constant and equal to the amount initially employed.

I claim:

1. The process of making a leuco-compound of a diaminodihydroxyanthraquinone monosulfonic acid, which comprises subjecting a diaminodihydroxyanthraquinone disulfonic acid to the action of zinc and sodium bisulfite.

2. The process of making a leuco-compound of a diaminodihydroxyanthraquinone monosulfonic acid, which comprises treating a diaminodihydroxyanthraquinone disulfonic acid with zinc and sodium bisulfite and adding thereto, during the treatment, sulfuric acid in amounts sufficient to maintain the presence of a bisulfite during the reaction.

3. The process of making a diaminodihydroxyanthraquinone monosulfonic acid, which comprises the process claimed under claim 1 and the subsequent treatment of said leuco-compound with a suitable oxidizing agent, whereby a diaminodihydroxyanthraquinone monosulfonic acid is produced.

4. The process of making a diaminodihydroxyanthraquinone monosulfonic acid in the form of its alkali metal salt, which comprises subjecting a diaminodihydroxyanthraquinone disulfonic acid to reduction by the action of zinc and sodium bisulfite and, without isolation, subjecting the reduction product thus obtained to oxidation by the action of atmospheric air in the presence of caustic alkali.

5. The process of making a diaminodihydroxyanthraquinone monosulfonic acid in the form of its alkali metal salt, which comprises subjecting a diaminodihydroxyanthraquinone disulfonic acid to reduction by the action of zinc and a small amount of sodium bisulfite and adding to the reaction mixture dur-

ing the reduction an amount of sulfuric acid sufficient to convert the sulfite present into bisulfite, and without isolation subjecting the reduction product thus obtained to oxidation 5 by the action of atmospheric air in the presence of caustic alkali.

6. The process of making a leuco-compound of paradiaminanthrarufine monosulfonic acid, which comprises subjecting paradi- 10 aminoanthrarufine disulfonic acid to reduc- 15 tion by the action of zinc and sodium bisul- 20 fite.

7. The process of making a leuco-compound of paradiaminanthrarufine monosulfonic acid, which comprises subjecting paradi- 15 aminoanthrarufine disulfonic acid to reduc- 20 tion by the action of zinc and sodium bisul- 25 fite, and during the reduction adding sulfuric acid in quantities sufficient to maintain the 30 presence of bisulfite during the reaction.

8. The process of making an alkali metal salt of paradiaminanthrarufine monosulfonic acid, which comprises subjecting paradiaminanthrarufine disulfonic acid to reduc- 25 tion by the action of zinc and sodium bisul- 30 fite, and without isolation subjecting the product thus obtained to oxidation by the 35 action of atmospheric air in the presence of caustic alkali.

30 9. The process of making an alkali metal salt of paradiaminanthrarufine monosulfonic acid, which comprises subjecting paradiaminanthrarufine disulfonic acid to reduc- 35 tion by the action of zinc and a small amount of sodium bisulfite and adding during the reduc- 40 tion a sufficient amount of acid to maintain the presence of bisulfite, and without isolation subjecting the product thus obtained to oxidation by the action of atmospheric air in the presence of caustic alkali.

10. In the production of a leuco-compound of diaminodihydroxyanthraquinone monosulfonic acid by subjecting diaminodihydroxyanthraquinone disulfonic acid to the 45 action of zinc and sodium bisulfite, the step comprising the addition, during the reaction, of sulfuric acid in an amount sufficient to maintain the presence of bisulfite.

11. In the production of a leuco-compound 50 of paradiaminanthrarufine monosulfonic acid by subjecting diaminanthrarufine disulfonic acid to reduction by means of zinc and sodium bisulfite, the step characterized by adding, during the reduction, an amount 55 of sulfuric acid sufficient to maintain the presence of bisulfite.

12. In the process of replacing a sulfonic group in a diaminodihydroxyanthraquinone disulfonic acid by an atom of hydrogen, the 60 improvement which comprises subjecting the diaminodihydroxyanthraquinone disulfonic acid to the action of zinc in the presence of sodium bisulfite.

13. The process of eliminating one sulfonic

acid group from a diamino-dihydroxy- 65 anthraquinone-disulfonic acid, which comprises subjecting the diamino-dihydroxy- 70 anthraquinone-disulfonic acid to the action of zinc and sodium bisulfite, the amount of bisulfite initially employed being insufficient 75 to react with all of the zinc and adding from time to time to the reaction mixture an amount of sulfuric acid sufficient to form bisulfite from the sulfite produced in the re- 80 action.

14. The process of removing one sulfonic acid group from para-diamino-anthrarufin- 85 disulfonic acid, which comprises treating para-diaminoanthrarufin disulfonic acid with zinc and sodium bisulfite and adding from 90 time to time to the reaction mixture sulfuric acid in amounts sufficient, but not in excess, to form bisulfite from the sulfite present.

15. The process of making a diamino- 85 dihydroxy-anthraquinone monosulfonic acid, which comprises subjecting a diaminodihydroxyanthraquinone disulfonic acid in the presence of water to the action of zinc and an alkali metal bisulfite, separating the solution containing the leuco-compound of the 90 monosulfonic acid thus obtained from any free zinc present, adding sufficient caustic alkali to the solution to render it alkaline and subjecting it to the action of a current of air whereby the leuco-compound is oxidized to 95 the dye, and then acidifying the mixture and isolating the dye.

16. In the production of a diaminodihydroxy-anthraquinone monosulfonic acid by 100 subjecting a diaminodihydroxyanthraquinone disulfonic acid to reduction with formation of a leuco-compound of the monosulfonic acid and subsequent oxidation of the leuco-compound to the dye in alkaline media, the improvement which comprises acidifying 105 the alkaline solution containing the dye prior to its isolation therefrom.

17. The process of making a diaminodihydroxyanthraquinone monosulfonic acid in 110 the form of its alkali metal salt, which comprises subjecting a diaminodihydroxyanthraquinone disulfonic acid to reduction by the action of zinc and a small amount of an alkali metal bisulfite and adding to the reaction mixture during the reduction a sufficient 115 amount of acid to maintain the presence of bisulfite.

18. The process of making an alkali metal salt of paradiaminanthrarufin monosulfonic acid, which comprises subjecting paradiaminanthrarufin disulfonic acid to reduc- 120 tion by the action of zinc and a small amount of sodium bisulfite and adding during the reduction an amount of sulfuric acid sufficient 125 to convert the sulfite present into bisulfite.

In testimony whereof I affix my signature.

DONALD G. ROGERS.
